UNITED STATES PATENT OFFICE.

JOSEPH A. MACLENNAN, OF PHILADELPHIA, PENNSYLVANIA, ASSIGNOR TO LINK-BELT COMPANY, OF CHICAGO, ILLINOIS, A CORPORATION OF ILLINOIS.

CONVEYER.

1,331,020.

Specification of Letters Patent. Patented Feb. 17, 1920.

Application filed May 2, 1917. Serial No. 165,836.

To all whom it may concern:

Be it known that I, JOSEPH A. MACLENNAN, a citizen of the United States, residing at Philadelphia, in the county of Philadelphia and State of Pennsylvania, have invented a certain new and useful Improvement in Conveyers, of which the following is a specification.

My invention relates to improvements in conveyers such as are practically applicable to the loading of boats and the like where it is desirable to convey or lower material from an elevated position to a lower position without breakage of the material. One object of my invention therefore is to provide means for lowering material such that the material may at all times flow in a continuous smoothly moving unhurried stream. Another object is to provide an extensible section which will maintain the material always under control as it is being fed downwardly and which will never let it drop or fall freely. Other objects will appear from time to time in the specification.

My invention is illustrated more or less diagrammatically in the accompanying drawings, wherein—

Figure 1 is a section through a boat showing apparatus in elevation with parts broken out;

Fig. 2 is a front elevation of the apparatus;

Fig. 3 is a detail of the lower end of the telescopic chute on a larger scale part in section and part in elevation.

Fig. 4 is a section on an enlarged scale showing a detail.

Like parts are indicated by like characters in all the drawings.

A is a ship or boat having an open loading hatchway A¹, adjacent the dock at A² upon which is the loading trestle A³. A⁴ is a dump track adapted to support any suitable railroad car not here illustrated. A⁵ is a working platform carrying the usual housing, containing the usual operating mechanism. This platform is supported on trucks A⁶, A⁶, and adapted to travel along the trestle. It is provided with a tower A⁷ thereupon and has pivoted thereon a boom A⁸ which boom is adapted to be rotated about its pivot point by a boom hoist A⁹ controlled by the usual drum A¹⁰ on the platform.

B is a track hopper adapted to be filled

with coal or other material from cars which travel along the track provided with a controlling gate B¹ operated by means of the belt B² whereby the flow of material may be controlled. This material is adapted to discharge into the hollow fixed column B³. This column is arranged in a fixed position on the structure or may be suspended from the platform as the case may be. Its front side is open as at B⁴. It is adapted to be closed by the foot B⁵ which carries an inclined feed platform B⁶. This foot is also adapted to carry a series of telescopic shutters B⁷. These shutters are adapted to close the front open side of the column and these shutters are so arranged that when the foot B⁵ is in raised position the plates are all supported by it. As the foot is lowered the column is closed above the foot so that there is always between the gate B¹ and the feed chute B³ a continuous column of material. The hoisting line B⁸ is provided whereby the foot and plates may be raised and lowered along the column at the will of the operator. The part B⁶ discharges into the adjustable chute B⁹ which may be raised and lowered by means of hoisting lines B¹⁰ so that its position may be changed in a vertical direction and so that its angle of inclination may be changed both at the will of the operator.

C is a hopper into which the chute B⁹ discharges. It forms the upper extremity of the telescopic chute or as I have called it an extensible section made up of a series of separate telescopic cylindrical sections C¹, C², C³, C⁴, C⁵. There may be more or less of these sections. They are arranged so that the upper one is the smaller, the lower one is the larger. This effectually prevents bridging of material across inside the section. The lower section is mounted on a housing C⁶. This housing is of larger diameter than the section and within this housing the section is enlarged as indicated at C⁷, and forms a narrow outlet throat with the conveyor belt C⁸. The enlarged open bottom end is closed by the carrier or conveyor belt C⁹ which belt is inclined toward the discharge point.

D is a motor. It drives a gear D¹ which drives a sprocket chain D² to drive the belt in a counter-clockwise direction so that the material which is fed down through the tele-

scopic chute or extensible section is fed up from beneath the column and discharged into the bottom of the boat. The housing C⁶ is suspended by hoisting lines D⁸ one on either side extending up over the boom A⁸ and controlled from the working platform by any suitable means not here shown.

It will be evident from my drawings that while I have shown an operative device, still many changes might be made both in size, shape and arrangement of parts without departing materially from the spirit of my invention and I wish therefore that my drawings be regarded as in a sense diagrammatic.

I have shown my extensible section as made up of cylindrical sections. Obviously it might be made of rectangular, quadrilateral or polygonal cross sections, it being only necessary that the section be hollow and closed so as to provide a vertically disposed chute or column or extensible section through which the material may descend.

The hopper C is supported by a suitable tackle from the frame arm A⁸ as indicated whereby it may be manipulated. I have not shown the specific means for fastening the separate sections of the telescopic tube together so that one can not slip through the other. Obviously there are thousands of ways in which this might be done, and since it forms no part of the subject matter of my invention I have not complicated the case by showing or describing such means.

The use and operation of my invention is as follows:

The operator will start in to fill the boat with the covered chute in the position shown in full lines and with the extensible section in its elevated position with all the telescoping sections one inside the other. If there is no material in the apparatus he will proceed to fill it up first having coal dumped in the track hopper then starting the controlling gate controlling the discharge from the track hopper to fill the upper end of the fixed boom. The material in the upper end of the fixed boom will travel down through the covered chute until that chute is filled. It will then fall into the hopper at the upper end of the extensible section and fill the upper part of the extensible section and this material which will drop down along the system will be stopped by the conveyer belt at the bottom of the extensible section. The material which will be added then will fill the entire section so that the material will be at rest and the section will be filled with it. When a boat is brought up to the wharf and is about to be loaded the operator will lower the extensible section meanwhile permitting the material to be fed from the track hopper through the system at such a rate of speed that the whole

system will be filled at all times, that is to say the material will be fed just fast enough to keep up with the increased capacity of the system as the extensible section is lengthened out. As soon as the housing at the lower end of the extensible section reaches the bottom of the boat the conveyer at the bottom of that housing will be started and the material will be fed away from the bottom of the extensible section into the bottom of the boat. This process will continue. The material following it will fill the system as it is taken away from the bottom until the boat is filled. As the boat is filled and the level of the material in the boat rises, the extensible section will be raised a short distance at a time until the entire boat is filled. When this is done the operation will be stopped and the apparatus drawn out of the boat ready for another filling.

The conveyer belt will at all times support the load and hold it stationary except when the belt is in motion. When it is in motion, it moves the material out and dumps it. At all other times the arrangement of the parts is such that the load column is firmly held.

I claim:

1. A conveyer comprising a downwardly conveying section adapted to deliver material in a solid column, means for delivering material to such section, and a laterally traveling discharge conveyer disposed across the lower end of such section so as to receive a descending column of material directly, and positively convey it to one side of such section, said conveyer being inclined upwardly away from the lower discharge end of such section.

2. The combination with a closed vertical feed tube, a discharge chute communicating directly with the bottom thereof and means for raising and lowering the chute, of a vertical telescopic feed tube associated at its upper end with the discharge end of the chute, means for raising and lowering the upper end of such telescopic tube, and for raising and lowering the lower end independent of the upper end and means at the bottom of the tube for controlling the discharge of material therethrough said control means comprising a traveling conveyer extending across immediately beneath the bottom of the telescopic tube adapted to support the lower end of the column of material therein and to feed such material to one side out of line with the column.

3. The combination with a vertically disposed closed discharge pipe for coal and the like of a conveyer belt extending across the bottom thereof and substantially closing such bottom, such belt being arranged to support directly the column of material in the tube and to discharge a stream of

material from the bottom of the column to one side of the direction of flow only when the conveyer is in operation, a housing inclosing said conveyer and adapted to completely close and surround the lower end of the tube except where the conveyer discharges outwardly through the wall thereof.

In testimony whereof, I affix my signature in the presence of two witnesses this 28th day of April, 1917.

JOSEPH A. MacLENNAN.
